APPLIANCE FOR ELEVATOR SAFETY DEVICES.

1,134,753.

Specification of Letters Patent.

Patented Apr. 6, 1915.

Application filed November 23, 1911. Serial No. 661,931.

To all whom it may concern:

Be it known that I, DAVID L. LINDQUIST, a subject of the King of Sweden, residing at Yonkers, in the county of Westchester and State of New York, have invented a new and useful Improvement in Appliances for Elevator Safety Devices, of which the following is a specification.

My invention relates to elevator safety devices and has for one of its objects the provision of a simple and efficient friction hitch or clamping appliance coöperating with the governor cable of an elevator and adapted primarily to prevent an excessive strain from being placed upon the safety cables and co-acting parts when the safety device is called into action.

Other objects of the invention will appear hereinafter, the novel combinations of elements being pointed out in the annexed claims.

The elevator safety device in general use at the present time, an example of which is known as the "Ellithorpe safety" has proven to be very satisfactory for elevators of moderate speed and rise, but at the present day when it is nothing unusual for an elevator car to travel to a great height at a normal speed of over 600 feet per minute a condition arises in connection with the operation of the safety device which is of serious import and which must be met in order that the safety device may be infallible in its operation regardless of the speed and distance of travel of the elevator car. The above-mentioned type of safety device comprises a cable drum located under the floor of the car and adapted when actuated to move outwardly a pair of wedges or toggle levers carried upon the ends of right and left hand threaded rods. These wedges or toggle levers effect the operation of corresponding clamp jaws which engage the guide rails of the elevator and the retarding action set up by the frictional engagement of the jaws on the rails brings the elevator car to rest. The rotation of the safety drum is effected by means of a cable coiled about the drum and connected to another cable which runs with the car during the normal operation thereof and which is substantially locked against movement by means of a speed governor when the car attains a predetermined speed in excess of the normal. As soon as the clamps controlled by the governor grasp the cable to apply the safety device this cable is retarded and no longer runs at the same speed as that of the car and the relative movement of the car with respect to the cable causes the safety drum to be rotated and the gripping clamps will be set up on the guide rails and the car retarded and finally stopped. During the interval of time required to set the clamping jaws on the guide rails the governor cable will in most cases come to rest or at least have its speed substantially reduced although the car is still traveling at a high speed. After the jaws are once set up on the guides it is seen that they can move no further and the safety drum will cease to rotate consequently the drum cable cannot further be pulled off. The velocity of the car is now suddenly imparted to the governor cable, which as before pointed out has been by this time substantially brought to rest by the clamps controlled by the governor, and it is clearly seen that this velocity which may be and frequently is over 800 feet per minute being imparted suddenly to the governor cable places the same under a sever strain which may be more than the cable can stand, with the result that either the governor cable or the cable connected to the safety drum must give way. The strain suddenly thrown upon the governor cable is not only that due to its inertia but also due in a large measure to the retardation introduced by the cable clamping jaws controlled by the governor. While this strain may be kept within reasonable limits when the speed of the car is not too high and when the inertia of the governor cable, or what amounts to practically the same thing, the height of car travel, is not too great, it is readily seen that some provision must be made to take care of this strain where the car travels to a considerable height at high speed. Where the car travel is in the neighborhood of 600 ft. at a normal car speed of 600 ft. per minute, the governor cable weighs approximately 720 pounds. Now at the instant of operation of the safety the car may reach a speed of 800 feet or more per minute, and when it is considered that the governor cable

weighing 720 pounds must be accelerated instantly from zero to 800 ft. per minute which condition is further augmented by the frictional engagement of the governor 5 clamps on the governor cable which amounts to approximately 800 pounds retarding force in addition to the inertia of the cable itself, it is readily seen that the strain suddenly placed upon the governor cable is 10 of great magnitude and the same has been the means of causing the cable to break. My invention is for the purpose of overcoming this great strain and protecting the cables and other apparatus under all conditions met in practice.

Broadly speaking my invention comprises an adjustable spring pressed friction hitch or cable clamp which is introduced between the end of the cable wound upon the 20 safety drum and the governor cable which permits of a relative slipping movement therebetween under excessive strain thereby relieving the cables associated with the safety device from all danger of breakage.

25 My invention is shown on the drawing accompanying this specification in which—

Figure 1 represents in elevation an elevator system embodying my invention; Fig. 2 is a sectional view of my friction cable 30 clamp; Fig. 3 is a side view in part section of Fig. 2; Fig. 4 is a sectional plan view of Fig. 2 taken on the broken line *a—a*; Fig. 5 is a plan view in part section of a supporting clamp used to attach the cable clamp 35 shown in Fig. 2 to the car; Fig. 6 is a dia-grammatic plan view in section of a safety device used for stopping the car in case of excess speed.

Like characters of reference denote similar parts in all the figures.

40 Referring to the drawing, the elevator car is designated by *C* and is suspended from the hoisting cables 1 which lead up over the overhead sheaves 2—2 carried in brackets secured to the beams 3 and which lead to any desired power driven hoisting mechanism such as an electric or other motor. To the bottom of the car is secured what is generally known as the safety plank 45 4 which carries the rail gripping jaws and their operating connections shown in detail in Fig. 6. The safety drum is designated by the numeral 5 and has wound upon it a cable 6 which is guided by a pair of sheaves 50 7 and is connected by means of a leaded clevis 8 to the clamping device 9. The latter is yieldingly secured to the car by means of a friction clamp 11 which is illustrated in detail in Fig. 5. The endless governor 55 rope 10 leads up and over the governor sheave 12 located at the top of the hatchway and passes around a weighted sheave 13 located at the bottom of the hatchway. The weighted sheave 13 is for the purpose of 60 maintaining the governor rope under a ten-

sion and its movement in an upward direction is limited by means of the guides 14. The governor shown is the well known Otis type of governor and operates upon excessive speed to raise the rod 15 thereby rotating the geared clutch members 16—16 so that they clamp the governor cable 10 and tend to bring it to rest. It should be noted that the clutch members 16—16 are not intended to jam the cable 10 so that it is positively held against movement but they are arranged so as to engage and clamp the cable 10 with a predetermined pressure which is regulated by the tension placed upon the spring 17 which bears against one of the 70 clutch members 16, said member being arranged so that it has a small bodily movement away from the opposite clutch member under pressure of the governor cable.

I will now give a brief description of the 85 Ellithorpe safety device shown in Fig. 6. The cable drum 5 is threaded upon a pair of oppositely threaded rods 18—18 which are carried by the supports 19—19 secured to and forming a part of the safety plank 4. The outer ends of these rods are connected by toggle levers 20—20 to corresponding 90 clamping jaws 21—21 which normally move freely over the guide rails 22—22 when the elevator is in its normal running condition.

If by reason of excessive car speed the drum 5 be rotated, the threaded rods 18—18 are screwed outwardly thereby causing the gripping jaws to be closed upon the guide rails and thus act as a powerful brake to effect 100 the retardation and final stopping of the car. The drum is rotated by means of the cable 6 which heretofore was always rigidly connected to the governor cable 10 so that

105 as soon as the governor acts and the cable 10 is substantially held against movement the continued movement of the car causes the cable 6 to be unwound from the safety drum thereby rotating the latter and effecting the application of the safety clamps to

110 the guide rails. As I have already pointed out the danger of having a rigid connection between the safety drum cables and the governor cable, I will now describe my invention as shown in detail in Figs. 2, 3, 4 115 and 5, which will obviate the danger. The device comprises a metal sliding hitch 23 of substantially cylindrical form the upper part of which is hollowed out and contains a conical split bushing 26. Surrounding this 120 bushing and inverted with respect thereto is another conical bushing 27 which is not split. A tension spring 28 is adapted to bear against the top of the bushing 27 and against a hollow plug 30 which is threaded 125 into the upper part 24 of the hitch 9 and which may be screwed down against the spring 28 with any desired amount of pressure and locked in place by means of the lock nut 32. The interior of the hollow 130

plug 30 is screw threaded and contains a sleeve 29 which is also threaded and which is screwed down hard against the conical bushing 26 and locked in position by means of the lock nut 31.

The purpose of the sleeve 29 is to prevent the conical bushing 26 from being moved upwardly upon the governor cable 10 and jamming the latter against movement there-
10 through. The governor cable passes loosely through the sleeve 29 but is gripped by the split bushing 26 with a power depending upon the tension placed upon the spring 28. It may be observed that the spring forces
15 the bushing 27 over the split bushing 26 and since these bushings are conical in form the pressure exerted by the spring tends to contact the split bushing and cause the latter to grasp the cable. The governor cable after
20 leaving the bushing 26 continues through a flared orifice 25 and is deflected from a vertical position by a roller 33 carried upon a stud 34 which passes through the hitch member and is riveted at either end. The gov-
25 ernor cable passes over another roller 33 mounted similar to the first roller and is again deflected so as to pass through a flared opening 37 at the lower end 36 of the hitch member. Intermediate the rollers 33-33 a
30 clevis 8 is secured by means of a rivet 35 each end of which is rounded over so as to form a pair of button heads 38-38. In order that the governor cable may travel with the car it is necessary to provide a connec-
35 tion therebetween, furthermore this connection must be yielding in its nature so that the governor cable may be disconnected from the car when the governor operates otherwise there can be no relative movement between
40 the governor cable and the car and the safety drum would not be rotated. This yielding connection I have shown in detail in Fig. 5 and the same comprises a pair of hinged members 39-39 pivoted at 40 to a bracket
45 41 which is rigidly secured to the car at any suitable place thereon. Each of the hinged members 39 is provided with a spherical re-
cess 42 which normally contains the button headed ends of the rivet 35 and the hinged
50 members are urged toward each other by means of a tension spring 43 whose tension may be regulated to the required amount by means of the adjusting nuts 44. This ar-
55 arrangement forms a simple and practical means for effecting a yieldable connection between the car and friction hitch 9 and the tension of the spring 43 may be regulated so as to vary the pull necessary to separate the connection between the car and the fric-
60 tion hitch.

It will be observed that the rollers 33-33 serve a double function, that is they not only tend to introduce a frictional retardation between the hitch 9 and the governor cable owing to the double deflection of the latter but

they also serve to guide the governor cable away from the clevis 8 so that there will be no interference therebetween when the safety device operates and the hitch 9 slides along the cable.

In view of the foregoing description, the operation of my invention is almost, if not quite, self explanatory. It will be readily seen that when the governor rotates at a speed in excess of what it was set for, the clutch members of the governor will grasp the governor cable and pull it loose from the yielding connection on the car. A pull is now exerted upon the cable 6 and the safety drum will be rotated thereby until the gripping jaws have moved up against the rails whereupon the drum will cease to rotate. By this time the governor has brought the governor cable substantially to rest and since the car is still traveling at high speed a sudden jerk is given to the governor cable, this jerk being resisted by reason of the inertia of the governor cable which is now at rest and by reason of the grip of the governor clutch on the cable. It is at once seen that this jerk 90 may be of such magnitude as to break the governor cable or the safety cable or both and it now becomes apparent wherein the great practical value of my friction hitch comes in. As soon as this jerk comes on the 95 cable the friction hitch 9 permits of a relative movement or slipping between the safety drum cable and the governor cable and since this friction may be adjusted to any desired amount the strain placed upon the cables 100 may be regulated at will and all danger of breakage of cables obviated without dimin-
ishing the efficiency of the car brake or gripping jaws in the least or lessening their retarding power.

My invention may be considered in one sense as a buffer device or shock absorber since it not only relieves the safety cables and all the apparatus associated therewith from excessive strains and shocks under all 110 conditions of operation, but at the same time there is no danger of having the gripping jaws of the safety device set up too hard on the guide rails which would tend to effect an excessive retardation of the car and cause the 115 same to be brought up too suddenly which of course is most undesirable. It is readily seen that the retardation of the car due to the action of the clamping jaws on the guide rails may be varied by adjusting the tension 120 of the spring 28 of the friction hitch. For example we will assume that this tension is of such an amount that the pull required to slide the hitch along the governor cable is about 700 pounds, it having been demon-
125 strated in practice that a pull of 700 pounds on the safety drum cable is ample to effect a satisfactory stop of the elevator car under average conditions of load and speed. If now the safety device operates, it is seen that 130

after the safety drum has been rotated to the extent of its movement, and the clamping jaws have been set up hard on the rails any increase in pull on the safety drum cable will 5 act to increase the grip of the clamping jaws on the guide rail until a maximum pull of substantially 700 pounds is placed upon the drum cable and this pull cannot exceed 700 pounds by any appreciable amount since any 10 tendency to increase it is counteracted by reason of the friction hitch sliding upon the governor cable.

I have shown and described my invention in connection with an elevator safety device 15 of well known type for the reason that it is particularly adapted to such use and also for use with elevator safety devices in general, but it will be observed that the same may be used without changing its principle 20 of operation or even its structure for many other purposes wherever it is desirable to form an adjustable yielding connection between a plurality of parts whether the same be cables, or other flexible members.

25 What I claim as new and desire to have protected by Letters Patent of the United States is:—

1. The combination with an elevator safety device, of a governor cable, a safety actuating cable, and a yielding connection therebetween.

2. The combination with an elevator safety device, of a governor cable, a safety actuating cable, and an adjustable yielding connection therebetween.

3. The combination with an elevator safety device, of a governor cable, a hitch yieldingly secured upon said cable, and a safety actuating cable fastened at one end to said hitch.

40 4. The combination with an elevator safety device, of gripping jaws adapted to engage the guide rails, a drum arranged to effect the operation of said jaws, a cable wound about said drum, means for effecting a pull on said cable, and a yielding connection between said cable and means.

5. In an elevator, the combination of a car, a safety device carried upon the car, an actuating cable associated with said 50 safety device, a governor cable connected to said actuating cable, and means for permitting a relative motion between said cables.

6. In an elevator the combination of a car, a safety device carried by the car, means for 55 effecting the operation of said safety device, a governor and governor cable, a clutch operated by the governor and adapted yieldingly to engage the governor cable upon excessive speed of the car, a friction hitch secured to said governor cable, and a connection between said friction hitch and said safety device operating means.

7. The combination with an elevator safety device, of means for applying said device, a 60 governor cable, a friction hitch between said

applying means and said cable, and spring pressed means for regulating the traction of said hitch to any predetermined amount.

8. In an elevator safety device, the combination of an actuating cable, a governor cable, a friction hitch arranged on the governor cable, and secured to said actuating cable, said hitch comprising an expanding bushing surrounding the governor cable, and means for effecting a contraction of said expanding bushing.

9. In an elevator safety device, the combination of an actuating cable, a governor cable, a friction hitch arranged on the governor cable and secured to said actuating cable, said hitch comprising an expanding bushing surrounding the governor cable, means for effecting a contraction of said bushing, and means for controlling the power of said last named means.

10. In an elevator, the combination of a safety device, a governor cable, a friction hitch carried by said cable, said hitch comprising an expansible bushing in contact with said cable, an additional bushing surrounding said expansible bushing and arranged to effect a contraction thereof, a spring bearing against said additional bushing, means for regulating the tension of said spring, and an operative connection between 95 said safety device and said hitch.

11. In an elevator, the combination of a safety device, a governor cable, a hitch carried upon said cable, spring pressed means for causing said hitch frictionally to engage 100 said cable, means for effecting a deflection in said cable to increase the frictional engagement of said hitch and cable, and an operative connection between said hitch and said safety device.

12. The combination with an elevator car, of a safety device for effecting a retardation of said car upon excessive speed, and frictional means for regulating said retardation to any predetermined amount.

13. The combination with an elevator, of gripping jaws adapted to engage the guide rails, a safety drum, operating means between the safety drum and gripping jaws, a cable connected to the drum and arranged to 115 effect the operation of said drum, and means for effecting a predetermined pull on said cable regardless of the load and speed of the car.

14. In an elevator, the combination of a 120 car, a retarding device carried upon the car, a governor cable normally running with the car, a drum, a drum cable connected to the retarding device; automatic means for effecting a movement of said governor cable relative to that of the car to effect the application of said retarding device, and means associated with said governor cable for limiting the amount of retardation of said device.

15. In an elevator, the combination of a 130

car and guide rails therefor, a safety device comprising clamping jaws adapted to engage the guide rails, automatic means for effecting the operation of said jaws, and 5 frictional means for regulating the gripping power of said jaws to any predetermined amount.

In testimony whereof, I have signed my name to this specification in the presence of two subscribing witnesses.

DAVID L. LINDQUIST.
